TYPEWRITER HOOD

Milon G. Logan, Albrook Field, C. Z.

Application December 4, 1941, Serial No. 421,662

4 Claims. (Cl. 197—186)

This invention relates to a hood for a typewriter, and its general object is to provide a hood that is primarily designed to protect the bearings and other parts of the machine from eraser droppings which not only cause the parts to bind, but result in premature wear thereof, particularly due to the fact that the so-called typewriter erasers include abrasive material and the like.

A further object is to provide a hood that covers the major portion of the top of the machine in advance of the platen to protect the ribbon spools and associated elements from dirt and dust, and the hood includes flanges normally underlying the platen to provide open end troughs for receiving the eraser droppings which can be readily removed from the troughs by a brush or by blowing the same therefrom.

Another object is to provide a hood that is permanently secured to the typewriter by being hingedly connected thereto, so that the hood can be swung to open position for ready access to the ribbon spools.

A further object is to provide a hood that can be attached to a typewriter, with minimum change to the structure thereof.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a perspective view, illustrating my device attached to a typewriter and looking toward the front thereof.

Figure 2 is a perspective view of the hood per se, looking toward the rear thereof.

Figure 3 is a side view, illustrating the hood in raised position in full lines and in lowered or normal position in dotted lines.

Referring to the drawing in detail, the letter A indicates the usual housing of a conventional typewriter, B the platen thereof and C a gage strip and card holder.

The hood is formed from sheet metal or any other suitable material to provide a flat top wall 1, side walls 2, and a front wall 3, the front and side walls merging into each other to provide rounded front corners to follow the shape of the housing, as shown in Figure 1, and the hood is

of elongated formation to fit that portion of the top of the housing in advance of the platen, so as to cover the same and enclose the ribbon spools and associated parts for protection thereof against dirt and dust.

The top wall is recessed centrally from the rear thereof, and disposed about the recess is a marginal depending flange 4, the recess being of a size to allow for free movement of the type bars and the flange being provided with rounded notches 5 for passage of the ribbon therethrough, as shown in Figure 1. The recess preferably increases in width toward the front thereof and the front is preferably of arcuate formation and merges into the sides in rounded formation, as best shown in Figure 1.

Formed on the rear of the top wall 1, upon opposite sides of the recess and extending from the latter to the side walls 2, are rearwardly directed flanges 6 that are downwardly curved from the top wall and have straight lower edges terminating in a plane above the lower edges of the front and side walls, for the lower edges of the flanges 6 to underlie the forward portion of the platen when the hood is in closed or normal position, as shown in dotted lines in Figure 3, to provide with the platen what may be termed troughs for receiving eraser droppings. The side walls 2 at the rear ends thereof are cut away as at 7, from their juncture with the rear edges of the flanges 6 for disposal flush with the outer ends of the latter, and such allows the hood to snugly fit the top of the housing.

The hood is permanently attached to the typewriter by being hingedly connected to the card holder C, and for that purpose, the card holder has its end portions bent forwardly at right angles to provide tabs 8. The marginal flange 4 extends rearwardly from the recess for disposal beyond the inner edges of the flanges 6 to provide substantially triangular shaped ears 9 which together with the tabs 8 have holes therein through which pass rivet like pivot pins 10 for hingedly connecting the ears to the tabs, thus allowing the hood to be raised to its full line position of Figure 3, so that ready access can be had to the ribbon spools.

When it is desired to make an erasure, the carriage is shifted for disposal of the typed matter to be erased, above one of the flanges 6, so that the eraser droppings will fall upon the same, and the droppings can be removed from the flanges 6 by a brush or by blowing the same therefrom, it being obvious that the droppings are brushed or blown toward the outer ends of

the flanges for passage exteriorly of the machine, thus preventing the droppings from coming in contact with the bearings, pivots and other parts of the machine to bind or cause premature wear thereof.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A hood for covering the upper portion of a typewriter in advance of the platen thereof, comprising a top wall and front and side walls, rearwardly extending flanges formed on the top and side walls and being curved downwardly from the top wall to underlie the forward portion of the platen to provide troughs for receiving eraser droppings, and means hingedly securing the hood to the typewriter.

2. A hood for covering the upper portion of a typewriter in advance of the platen thereof, comprising a top wall and front and side walls, rearwardly extending flanges formed on the top and side walls and being curved downwardly from the top wall to underlie the forward portion of the platen to provide troughs for receiving eraser droppings, said top wall being recessed from the rear thereof to provide a passage for the type bars of the typewriter, a depending flange formed on the top wall about the recess, and ears formed on the rear ends of the depending flange and adapted to be pivotally secured to the typewriter for hingedly connecting the hood thereto.

3. In a device for covering the upper portion of a typewriter in advance of the platen thereof, a hood comprising a top wall and front and side walls, rearwardly extending flanges formed on the top and side walls and being curved downwardly from the top wall to underlie the front portion of the platen in close proximity thereto to provide open end troughs for receiving eraser droppings, said top wall being recessed from the rear thereof to provide a passage for the type bars of the typewriter, a depending flange formed on the top wall about the recess and being provided with notches for the passage of the typewriter ribbon therethrough, said recess increasing in width toward the front of the top wall and having its forward portion curved rearwardly, and means for hingedly securing the hood to the typewriter including triangular shaped ears formed on the rear ends of the depending flanges for disposition rearwardly of the curved flanges, and forwardly extending tabs formed on the ends of the card holder of the typewriter and having the ears pivotally connected thereto.

4. A hood for covering the upper portion of a typewriter in advance of the platen thereof, comprising a top and front and side walls, rearwardly extending flanges formed on the top and side walls and curved downwardly to underlie the forward portion of the platen to provide troughs, said top wall being recessed from the rear thereof and provided with downwardly extending flanges, and means formed on the flanges for pivotally securing the same to the typewriter.
